CLAIM

I claim the ornamental design for a wicker chair, as shown and described.

DESCRIPTION

FIG. 1 is an upper perspective view of a wicker chair; FIG. 2 is a lower perspective view of the design shown in FIG. 1;

FIG. 3 is a front plan view of the design shown in FIG. 1; FIG. 4 is a rear plan view of the design shown in FIG. 1; FIG. 5 is a left side plan view of the design shown in FIG. 1;

FIG. 6 is a right side plan view of the design shown in FIG. 1;

FIG. 7 is a top plan view of the design shown in FIG. 1; FIG. 8 is a bottom plan view of the design shown in FIG. 1; and,

FIG. 9 is a close-up view of the wicker pattern of the design shown in FIG. 7.

The dash-dot broken lines shown in FIGS. 7 and 9 represent boundaries of the claimed design of the enlarged view, and form no part thereof. The shade lines shown represent surface shading and not surface ornamentation, color, or material type.
